Attorney

UNITED STATES PATENT OFFICE

MORTON O. BLAND, OF SHELBYVILLE, INDIANA

TOY

Application filed December 5, 1929. Serial No. 411,958.

This invention relates to toys of that type known as whirligigs and embodying a rotatable member, sound producing devices carried by the rotatable member, and a looped flexible operating member passing through openings in the rotatable member.

The invention has for one of its objects to provide a toy of the character stated wherein the rotatable member shall embody a construction adapted to provide passages arranged in the interior of the member and open at their ends, the passages constituting sound producing elements and the sound resulting from the flowing of air through the passages during the rotation of the member.

The invention has for a further object to provide a toy of the character stated wherein the rotatable member shall be made of cardboard or the like material and wherein this member shall be provided at its axial center with knobs adapted to insure the steady rotation of the member and adapted to prevent the enlargement of the holes provided therein for the reception of the operating member.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of the toy;

Figure 2 is a sectional view taken on the plane indicated by the line 2—2 of Figure 1;

Figure 3 is a view in end elevation of the operating member, and

Figure 4 is a sectional view taken on the plane indicated by the line 4—4 of Figure 2.

Referring in detail to the drawing, 1 designates the rotatable member of the toy. This member, which is preferably made of cardboard, is of angular formation in contour, and embodies outer flat plates 2 and 3 and an inner corrugated plate 4. The outer plates may be ornamented, as shown in Figure 2, or in any other suitable manner.

The plates 2, 3 and 4 may be glued or riveted together. The outer plates 2 and 3 close

the sides of the channels of the inner plate 4 to provide parallel air passages 5 which extend from one edge of the rotatable member 1 to an opposite edge thereof and are fully open at their ends.

The rotatable member 1 is provided with openings 6 which are spaced equally from the axial center of the member and are larger than and provide for the reception of the sides 7 of a looped operating member 8. The rotatable member 1 is provided at its axial center and upon opposite sides thereof with knobs 9 which may be glued or riveted to the member. The knobs 9 are preferably made of wood and have flat inner surfaces and convex outer surfaces. The knobs 9 extend outwardly beyond the inner wall portions of the openings 6 to permit the sides 7 of the operating member 8 to contact with the edges thereof.

The operating member 8 is flexible, and is preferably made of cord. The operating member 8 is provided at its ends with gripping elements 10 which are preferably in the form of finger receiving rings.

The toy is operated by first intertwisting the sides 7 of the operating member 8, and by thereafter alternately stretching and releasing the operating member. During the rotation of the member 1, air flows through the passages 5 and in flowing therethrough produces a sound. The knobs 8 insure the steady rotation of the member 1, and also, since they extend outwardly beyond the inner wall portions of the opening 6, prevent the wearing away of the rotatable member 1 by the sides 7 of the operating member 8, it being noted that the sides of the operating member bear against the edges of the knobs, with the result that the strain tending to cause the centers of the sides of the operating member to approach each other is borne by the knobs.

It should be also apparent that, while the rotatable member 1 is made of comparatively light materials, it is strong and durable and will rotate steadily, and that furthermore, the toy may be manufactured and sold at a comparatively low cost.

While I have described the principle of the

invention, together with the article which I now consider the preferred embodiment thereof, it is to be understood that the article shown is merely illustrative and that such changes may be made, when desired, as fall within the scope of the invention as claimed.

I claim:—

- 5 1. A toy comprising a rotatable member made of cardboard and provided at opposite sides of its axial center with openings, knobs secured to opposite sides of said member between said openings and extending outwardly for a slight distance beyond the inner wall portions of the openings, and a looped flexible operating member having its sides extending through said openings, contacting with the edges of the knobs.
- 10 2. A toy comprising a rotatable member consisting of outer flat plates and an inner corrugated plate, said outer plates closing the sides of the channels of said inner plate to provide parallel air passages open at their ends and arranged at opposite sides of the axial center of said member and having their ends arranged at opposite edges of said members, said member being provided at opposite sides of its axial center with openings, and a looped flexible operating member having its sides extending through said openings.
- 15 3. A toy comprising a rotatable member of angular formation in contour and embodying flat outer plates and a corrugated inner plate, said plates being made of cardboard and said outer plates closing the sides of the channels of said inner plate to provide air passages extending from one edge to an opposite edge of said member and open at their ends, said member being provided in opposite sides of its axial center with openings, knobs made of wood and secured to said members at the axial center and in opposite sides thereof, the knobs extending outwardly beyond the inner wall portions of said openings, and a looped flexible operating member having its sides passing through said openings and contacting with the edges of the knobs, the openings being larger, diametrically than the sides of the operating member.
- 20 4. In testimony whereof I hereunto affix my signature.

MORTON O. BLAND.
